United States Patent Office.

JAMES GORTON, OF COHOCTON, NEW YORK.

Letters Patent No. 90,355, dated May 25, 1869.

IMPROVED ROAD-SCRAPER.

The Schedule referred to in these Letters Patent and making part of the same.

To all whom it may concern:

Be it known that I, JAMES GORTON, of Cohocton, in the county of Steuben, and in the State of New York, have invented certain new and useful Improvements in Scrapers; and I do hereby declare that the following is a full, clear, and exact description thereof, reference being had to the accompanying drawings, and to the letters of reference marked thereon.

In the annexed drawings, making part of this specification—

A represents a metallic frame, which consists of two parallel bars placed at a suitable distance, curved as represented, and connected together by the two cross-bars B B.

Handles C C are formed on the rear ends of the parallel or side bars of the frame.

E represents a double scraper constructed upon any of the well-known plans, and made of metal, or metal bound.

This scraper is pivoted at its centre *a a*, between the two side bars of the frame, and revolves upon this pivot.

D D represent two levers pivoted, through ears formed upon them, to the side bars of the frame at *xx*.

Springs *e e*, secured to the side bars, press these levers from said bars at their rear ends. On the inside of the forward ends of the levers D, are pins, *dd*, which pass through openings made to receive them in the side bars, and then take into holes made in the sides of the scraper.

By pressing in the rear ends of the levers, their rear ends recede from the side bars and the pins *d*, leaving the holes in the scraper, it is allowed to revolve upon its centre pivot. When the scraper has made a half revolution, the levers D being free, the pins *d d* take into the holes in its sides and station it.

The operator, who stands in rear of the scraper, with his hands upon the handles C C, easily forces in the rear ends of the levers, so as to free the scraper and allow it to partially revolve. The moment the scraper is released, the operator removes his hand from the levers, and when the scraper has made its half revolution by being dragged forward, the pins *d d* take quickly into the holes, as has been described, stationing it until it is necessary to have it revolve again.

Having thus fully described my invention,

What I claim as new, and desire to secure by Letters Patent, is—

The double revolving scraper E, pivoted to the metallic frame A, at its centre, said frame being provided with horizontal levers D D and springs *e e*, for securing the scraper, and allowing the same to revolve, the whole being constructed, arranged, and operating as set forth.

In testimony that I claim the foregoing, I have hereunto set my hand and seal, this 6th day of June, 1867.

JAMES GORTON. [L. S.]
